United States Patent Office

Des. 210,657
Patented Apr. 2, 1968

210,657

REARVIEW MIRROR

Earl Bullis, Jr., Fairfield, Conn., assignor to The Roberk
Company, Shelton, Mass., a corporation of Connecticut

Filed Mar. 10, 1967, Ser. No. 6,162

Term of patent 3½ years

(Cl. D14—6)

Fig. 1

Fig. 2

Fig. 3

Fig.4

Fig.5

FIG. 1 is a side view of the rearview mirror showing my new design;

FIG. 2 is a back view of the rearview mirror;

FIG. 3 is a top view of the rearview mirror;

FIG. 4 is a front view of the mirror; and

FIG. 5 is a longitudinal sectional view of the mirror casing.

I claim:

The ornamental design for a rearview mirror, as shown.
